UNITED STATES PATENT OFFICE.

CLARENCE W. CROOKSHANK, OF SAN DIEGO, CALIFORNIA.

CAP FOR BOTTLES AND OTHER CONTAINERS.

Application filed April 12, 1926. Serial No. 101,319.

My invention relates to caps for bottles and other containers.

The objects of my invention are: first, to provide a cap of this class which may be 5 bottle or other similar container and which may be readily removed therefrom without the necessity of a bottle opener or other similar instrument, which openers or other instruments are not always at hand when 10 desiring to remove the caps from bottles or other similar containers; second, to provide a cap of this class having means intermediate its edge to permit ready insertion of a cap prying member therethrough 15 for prying the cap from a bottle or other similar container, but which cap is of such construction as to thoroughly seal the normally open end of the bottle or other container; third, to provide a cap of this class 20 through which any small rigid instrument, such as a knife, fork, nail, piece of wood, or the like, may be inserted for prying off the cap; fourth, to provide a cap of this class having an opening at its middle portion and 25 a gasket at its inner side and means, such as paraffin or other suitable material, for sealing the openings, but which paraffin or other suitable sealing material may be readily removed or forced through the opening 30 for inserting a cap prying-off member through the opening for prying off the cap from the bottle or other container; fifth, to provide a cap of the class mentioned having means in the form of a label at its outer 35 side for protecting the sealing means over the opening; sixth, to provide as a whole a novelly constructed cap of this class, and seventh, to provide a cap of this class which is very simple an economical of construction, 40 durable, and which will not readily deteriorate or get out of order.

With these and other objects in view, as will appear hereinafter, my invention consists of certain novel features of construction, 45 combination and arrangement of parts and portions, as will be hereinafter described in detail and particularly set forth in the appended claims, reference being had to the accompanying drawings and to the characters of reference thereon, which form a part 50 of this application, in which:

Figure 1 is an enlarged top view of my cap in its preferred form of construction for sealing or capping bottles, certain parts 55 and portions thereto being broken away and in section to facilitate the illustration; Fig.

2 is a sectional view thereof, taken through 2—2 of Fig. 1, and Fig. 3 is a fragmentary elevational view of a bottle, showing my cap secured over the open end thereof. 60

Like characters of reference refer to similar parts and portions throughout the several views of the drawings.

My cap, as illustrated in the drawings, 65 consists essentially of the cap member 1, a gasket 2, a plastic material 3, a sealing plastic material 4, and a label 5.

The cap member 1 is made and shaped substantially the same as bottle caps now in common use, the same being made of an 70 inverted, substantially cup-shaped, metallic shell, the depending edge 1^a of which is crimped and adapted to be pressed around the open end of a bottle. The cap member 75 1 of my construction, however, is provided in the middle portion of the upper plate portion of 1^b thereof with an opening 1^c, the walls forming said opening being preferably rolled inwardly slightly so as to provide a relatively deep opening. On the inside of the cap member or shell 1 is positioned a gasket member 2, preferably of cork or other suitable material, which is preferably secured to the inner side of the plate portion 1^b by a plastic or cementing material 80 85 90 95 3. Said gasket member 2 extends over the opening 1^c, as shown best in Fig. 2. In the opening 1^c is provided sealing material, such as paraffin, indicated by 4 in Fig. 2. This paraffin 4, or other suitable plastic material, is poured in a plastic state over the portion of the gasket member 2 exposed in the opening. Over the outer side of the plate portion 1^b of the cap member or shell is adhesively secured a label 5, which covers the 95 paraffin 4 and protects the same from the sun or from being otherwise destroyed or punctured.

In order to remove the cap from the bottle or other container, any suitable instrument, 100 such as a knife, fork, nail or piece of wood may be inserted through the label 5, the paraffin or other sealing material 4 and the gasket member 2, and the cap thus pried off without injuring the bottle or other container in any way.

It is understood, of course, that the label 5 and even the sealing material 4 may be done away with if desired, and the opening 1^c may be positioned near the edge of the 110 cap if desired; and though I have otherwise shown and described a particular construc-

tion, combination and arrangement of parts and portions, I do not wish to be limited to this particular construction, combination and arrangement nor to the suggested modifications, but desire to include in the scope of my invention, the construction, combination and arrangement substantially as set forth in the appended claims.

Having thus described my invention, what I claim as new and desire to secure by Letters Patent is:

- 10 1. In a cap for bottles adapted to contain effervescent beverages, a metallic shell having a securing portion at its outer edge and a opening at its middle portion, a cork sealing gasket member positioned on the inner side of said shell and over said opening, and
- 15

plastic material positioned in said opening over said gasket.

2. In a cap for bottles adapted to contain 20 effervescent beverages, a metallic shell having a securing portion at its outer edge and an opening at its middle portion, a cork sealing gasket member positioned on the inner side of said shell and over said opening, 25 plastic material positioned in said opening over said gasket, and protective means secured over the outer portion of said shell and over said plastic material.

In testimony whereof, I have hereunto set 30 my hand at San Diego, California, this 1st day of April, 1926.

CLARENCE W. CROOKSHANK.

CERTIFICATE OF CORRECTION.

Patent No. 1,674,951.

Granted June 26, 1928, to

CLARENCE W. CROOKSHANK.

It is hereby certified that error appears in the printed specification of the above numbered patent requiring correction as follows: Page 1, line 5, before the word "bottle" insert the words "securely fastened over the opening of a"; line 39, for the word "an" read "and"; line 55, for the word "thereto" read "thereof"; line 77, strike out the word "of"; page 2, line 15, claim 1, for the article "a" first occurrence read "an"; and that the said Letters Patent should be read with these corrections therein that the same may conform to the record of the case in the Patent Office.

Signed and sealed this 25th day of September, A. D. 1928.

Acting Commissioner of Patents.

tion, combination and arrangement of parts and portions, I do not wish to be limited to this particular construction, combination and arrangement nor to the suggested modifications, but desire to include in the scope of my invention, the construction, combination and arrangement substantially as set forth in the appended claims.

Having thus described my invention, what I claim as new and desire to secure by Letters Patent is:

- 10 1. In a cap for bottles adapted to contain effervescent beverages, a metallic shell having a securing portion at its outer edge and a opening at its middle portion, a cork sealing gasket member positioned on the inner side of said shell and over said opening, and
- 15

plastic material positioned in said opening over said gasket.

2. In a cap for bottles adapted to contain 20 effervescent beverages, a metallic shell having a securing portion at its outer edge and an opening at its middle portion, a cork sealing gasket member positioned on the inner side of said shell and over said opening, 25 plastic material positioned in said opening over said gasket, and protective means secured over the outer portion of said shell and over said plastic material.

In testimony whereof, I have hereunto set 30 my hand at San Diego, California, this 1st day of April, 1926.

CLARENCE W. CROOKSHANK.

CERTIFICATE OF CORRECTION.

Patent No. 1,674,951.

Granted June 26, 1928, to

CLARENCE W. CROOKSHANK.

It is hereby certified that error appears in the printed specification of the above numbered patent requiring correction as follows: Page 1, line 5, before the word "bottle" insert the words "securely fastened over the opening of a"; line 39, for the word "an" read "and"; line 55, for the word "thereto" read "thereof"; line 77, strike out the word "of"; page 2, line 15, claim 1, for the article "a" first occurrence read "an"; and that the said Letters Patent should be read with these corrections therein that the same may conform to the record of the case in the Patent Office.

Signed and sealed this 25th day of September, A. D. 1928.
